DESIGN FOR A TRANSIT TRANSFER

Fred P. Hamilton, Jr., Omaha, Nebr.

Application November 14, 1940, Serial No. 96,572

Term of patent 14 years

To all whom it may concern:

Be it known that I, Fred P. Hamilton, Jr., a citizen of the United States, residing at Omaha, in the county of Douglas and State of Nebraska, have invented a new, original, and ornamental Design for a Transit Transfer, of which the following is a specification, reference being had to the accompanying drawing, forming a part thereof.

Fig. 1 is a face view of the transit transfer, showing my design; and

Fig. 2 is an edge elevational view thereof.

I claim:

The ornamental design for a transit transfer, as shown.

FRED P. HAMILTON, JR.
